UNITED STATES PATENT OFFICE.

JOSEPH E. FAWELL, OF PITTSBURGH, PENNSYLVANIA, ASSIGNOR TO MACKINTOSH-HEMPHILL & COMPANY, OF PITTSBURGH, PENNSYLVANIA, A CORPORATION OF PENNSYLVANIA.

ROLLING-MILL.

1,233,209.

Specification of Letters Patent. Patented July 10, 1917.

Application filed October 30, 1915. Serial No. 58,893.

To all whom it may concern:

Be it known that I, JOSEPH E. FAWELL, residing at Pittsburgh, in the county of Allegheny and State of Pennsylvania, a citizen of the United States, have invented or discovered certain new and useful Improvements in Rolling-Mills, of which improvements the following is a specification.

The invention described herein relates to certain improvements in manipulating mechanism for rolling mills, and has for its object the operation of such mechanism by and simultaneous with the shifting of the rolls. The invention is hereinafter more fully described and claimed.

In the accompanying drawings forming a part of this specification, Figure 1 is a top plan view of a rolling mill embodying the improvements claimed herein; Fig. 2 is a sectional elevation of the same; Figs. 3 and 4 are views similar to Figs. 1 and 2 showing the improvements in connection with another form of mill proper; Figs. 5 and 6 are transverse sections on planes indicated by the lines V—V and VI—VI, Fig. 1.

The improvements claimed herein are shown and described in connection with the type of mills in which the reducing rolls are nonreversible, the reversing of the article being effected by changing the positions of the rolls, but the invention is not limited to use in connection with the types shown.

In Figs. 1 and 2 the mill which is of the Fawell type consists of two pairs of rolls 1 and 2 so mounted in movable housings 3, that when one pair of rolls are in operative relation to the feed tables, the upper roll of the other pair will be below a plane tangential to the rollers of the feed table. Suitable mechanism (not shown) is employed for so rotating the rolls that one pair will move the article in one direction and the other pair feed the article in the opposite direction.

In Figs. 3 and 4 is shown the Lamberton type of mill in which a single pair of reducing rolls are mounted in housings 6 rotatable through an arc of 180 degrees, and are driven by suitable non-reversing mechanism (not shown). Stationary feed tables 7 and 8 provided with reversible feed rollers are arranged on opposite sides of the mill. Buggies 9 are arranged below the feed tables having their supporting wheels

mounted on rails 10 parallel or substantially parallel with the axes of the feed rollers. These buggies are provided with standards 11 projecting up between adjacent rollers and having guide bars 12 secured thereto. These guide bars extend along the tables at rigid angles to the axes of the rollers and consequently substantially parallel, the lines of movement of articles being reduced by the rolls. As the guide bars are shifted by the buggies any article or articles lying between the bars will be moved in directions parallel with the axes of the rolls into alinement with a pass in the rolls.

The buggies are connected by rods 13 to arms 14 of bell cranks 15, which have their other arms connected by a rod 16 to a rocker arm 17 of the shaft 18. In the construction shown in Figs. 1, 2 and 5, the shaft 18 is provided with a second rocker arm 19 which is connected by a pitman 20 to the housing carrying the two pairs of reducing rolls so that by rotating the shaft 18, the housing is shifted to bring the other pair of rolls to operative position and the guide bars are also shifted to bring the article into alinement with the desired pass. The rotation of the shaft 18 is preferably effected by means of fluid pressure cylinders 21 having their piston rods connected to a rocker arm 22 on the shaft.

As in the Lamberton mill shown in Figs. 3 and 4, the housing must be rotated through an arc of 180 degrees, a rack bar 22^a adapted to be reciprocated by fluid pressure cylinders 23 engages a pinion 24 on the shaft 25, having keyed thereon a pinion 26 intermeshing with a circular line of teeth on the housing of the rolls. The shaft also carries a beveled pinion 27 intermeshing with a correspondingly shaped pinion 28 on shaft 29 which is provided with rocker arms 30 connected by pitmen 31 to the buggies carrying the guide bars of the feed tables. The pinions 27 and 28 are so relatively proportioned that the movement of the pinion 27 through an arc of 180 degrees will effect the required angular movement of the rocker arms 30, and consequent shifting of the guide bars across the table.

As it is frequently desirable to turn the billet or other article intermediate successive reductions, provision is made for such turning while the article is being shifted across the feed table. A suitable construc-

tion for such purpose is shown in Fig. 6, and consists of fingers 32 arranged in guides 33 on the standards 11, and having their lower ends connected to one arm of bell-crank 34 pivotally mounted on the standards or buggies, the other arms of the bell-crank being tied to a side-bar 35 of the feed table by links 36, or otherwise anchored, as against movement with the buggies. As the buggies are moved to the right in Fig. 6, the pivotal points of the bell-cranks will be moved, and the free arms of the latter will raise the fingers, which engaging a corner of the billet or other article will turn it axially.

While the mechanisms shown and described herein are well adapted for shifting the roll housings the guide bars and the turning devices, other means will readily suggest themselves to the skilled engineer, and hence within the scope of the claims, the invention is not limited to the specific constructions shown.

I claim herein as my invention:

1. In a rolling mill, the combination of reducing rolls, a feed table, means for turning articles lying on the table, and means for

simultaneously shifting the rolls and turning means.

2. In a rolling mill, the combination of reducing rolls, a feed table, guide bars movable across the table, means for turning an article lying on the table, and means for simultaneously shifting the rolls, guide bars and turning means.

3. In a rolling mill, the combination of a pair of rolls, means for moving said pair of rolls in the arc of a circle, a feed table stationary as against vertical movement, and means operative by the roll moving means for moving an article across the front of the reducing rolls.

4. In a rolling mill, the combination of a rotatable housing, two pairs of nonreversing rolls mounted in said housing, means for turning the housing, and means operative by the housing turning means for moving an article laterally across the front of the rolls.

In testimony whereof, I have hereunto set my hand.

JOS. E. FAWELL.
